COKE OVEN DOOR

Wilhelm Beimann, Bochum, Germany; Elizabeth Beimann, Bochum, Germany, administratrix of said Wilhelm Beimann, deceased, assignor, by mesne assignments, to the firm Otto-Wilputte Ovenbouw Maatschappij N. V., The Hague, Netherlands, a corporation of the Netherlands

Application September 29, 1934, Serial No. 746,116
In Germany January 5, 1933

12 Claims. (Cl. 202—248)

The present invention relates to coke ovens and particularly to coke ovens of the type comprising horizontally elongated open ended coking chambers arranged side by side with a flued heating wall between each adjacent pair of coking chambers. In such ovens each end of each coking chamber is normally closed by a door including an inner plug portion of refractory material extending into the coking chamber and an outer metallic portion which cooperates with a metallic door frame member surrounding the doorway and fixed in the oven brickwork to provide a packed or gas-tight joint between the door and door frame, the door and door frame members having 10 cooperating parts by which the door is releasably locked in its closed position. In such ovens vertically disposed metallic buckstays are provided at the ends of the heating walls to reinforce and armor the latter, and heretofore it has been 15 customary to employ door frame members each having a portion at each side of the door way which is interposed between the brickwork at the end of the adjacent heating wall and a buckstay in front of the latter so that the door frames are 20 secured in place by the buckstays and cannot be 25 removed without removing the buckstays.

The present invention has for its objects improvements in the construction and mounting of the door frame members, and in the relation to 30 the buckstays of the door frame members whereby the latter may be readily removed for repairs or replacement, and for repairs to the brickwork at the ends of the heating walls, without removing or loosening either the buckstays at the ends 35 of the heating wall or the metallic flash plates which may be interposed between the heating wall ends and the buckstays, and whereby the door frame members may be made appreciably lighter in weight than the door frame members heretofore 40 customarily employed in coke ovens of the above mentioned type.

In accordance with the present invention each door frame member is located between, and does not extend back of, the adjacent buckstays at opposite sides of the corresponding doorway, but is rigidly connected to said buckstays, or to parts in rigid engagement with the latter, by connecting means distributed along the entire height of the doorway and adjustable or detachable to permit 50 the removal of the door frame member without interfering with the general operation of the coke oven battery.

The various features of novelty which characterize my invention are pointed out with particularity in the claims annexed to and form-

ing a part of this specification. For a better understanding of the invention, however, and the advantages possessed by it reference should be had to the accompanying drawings and descriptive matter in which I have illustrated and described a preferred embodiment of the invention. 5

Of the drawings:

Fig. 1 is a side elevation of a portion of a horizontal chamber coke oven battery with the doors removed from the ends of the coking chambers 10 shown;

Fig. 2 is a horizontal section on the line 2—2 of Fig. 1, with the door in place in one and removed from the other of the two doorways shown;

Fig. 3 is a view similar to Fig. 1 showing a second embodiment of the invention;

Fig. 4 is a horizontal section generally similar to Fig. 2 and taken on the line 4—4 of Fig. 3;

Fig. 5 is a view generally similar to Fig. 1 illustrating a third embodiment of the invention; and 20

Fig. 6 is a horizontal section on the line 6—6 of Fig. 5.

In the embodiment of the invention illustrated in Figs. 1 and 2, the refractory brickwork of the oven heating walls 1 is held together by U-shaped 25 iron buckstays 2, there being two buckstays 2 in front of and bearing against each heating wall end. A metallic door frame 4 is provided for the reception of the door 8 removably closing each end of each of the horizontally elongated coking 30 chambers 3 which alternate with the heating walls 1. Ordinarily and as shown, each door frame member 4 is in the form of a hollow rectangular frame, the sides of which are normally received in recesses 1r provided for the purpose 35 at the adjacent corners of the adjacent heating walls, the sides of member 4 not projecting inwardly across the corresponding chamber 3. A packing 1s of asbestos or other suitable material shown as interposed between each door frame 40 and the oven brickwork may be employed to insure a joint tight seal between the door frame and oven brickwork. As shown the door frames 4 are formed with lugs 4' which carry hooks 5 engaged by bolts or locking bars 9 secured to the 45 outer metallic portion of the corresponding door 8. Each door 8 comprises an inner plug portion 8' of refractory material which in the closed position of the door extends into the corresponding coking chamber 3 as shown at the lefthand 50 side of Fig. 2. As shown in Figs. 1 and 2, each door frame member 4 is formed with a machined surface 6 which in the closed position of the door is engaged by a joint sealing portion 7 of the door to form a gas tight seal of known type.

As shown in Figs. 1 and 2, recesses are provided in the ends of each brickwork heating wall 1 behind the corresponding buckstays 2 to receive bars 10, the ends of which normally extend in front of the door frame members 4 and serve as door frame holding lugs. As shown in Fig. 1 and at the left-hand sides of Figs. 1 and 2, screws 11 threaded through the ends of the bars 10 in front of each door frame member 4 engage outer surface portions of the door frame member and firmly press the latter against the ends of the corresponding heating walls. As shown at the right-hand sides of Figs. 1 and 2, wedges 12 between the ends of the bars 10 and adjacent portions of the door frame member 4 are used in lieu of the screws 11 to secure the door frame member. As shown in Fig. 1, each side of each door frame is in operative engagement with four bars 10 at suitably distributed distances along the length or vertical height of the door frame, and each of the bars 10 cooperating with the door frame at one side of each heating wall is alongside a corresponding bar in engagement with the other frame at the opposite side of the heating wall.

With the construction shown in Figs. 1 and 2, when it becomes desirable to remove a door frame 4, the corresponding screws 11 or wedges 12 are removed, and the corresponding bars 10 are then moved longitudinally to clear the side edges of the door frame member which may then be withdrawn from its seal. Conveniently the door frame may be withdrawn with the corresponding door 8 locked in place therein by means of the usual door handling machine provided at the corresponding side of the battery to move the doors into and out of place in the normal operation of the battery. The removal of the door frame members provided for not only permits door frame repairs or replacements but also facilitates repairs of the adjacent end portions of the heating walls. With the construction described, the removal of a door frame member 4 exposes enough of the adjacent heating wall ends to permit the chipping out of one or more of the heating wall bricks 1a, 1b, 1c, 1d, which in Fig. 2 are shown as forming the outer portion of each heating wall 1, and the sides of the end heating wall flue 1e. As those skilled in the art understand, the end portions of the heating walls 1 ordinarily deteriorate more rapidly than the intermediate portions of the wall, and the facility provided by the present invention for access to the end portions of the heating walls for repairs without interfering with the general operation of the coke oven battery is an inherent and practically important advantage of the invention. Preparatory to the return of each door frame member which has been removed, new packing material 1s if needed may be put in place.

In the embodiment of the present invention shown in Figs. 3 and 4, the door and door frame members 8A and 4A respectively are similar in their general construction and disposition to door and door frame members of the construction shown in Figs. 1 and 2 described, but as shown the door frame members 4A are formed with side flanges 410 which overlap metallic flash plates 16 interposed between the sides of the brickwork heating wall 1 and the corresponding buckstays 14. As shown in Figs. 3 and 4, there is a single buckstay 14 of I-beam form in front of each heating wall end. In the arrangement shown in Figs. 3 and 4, the means employed for securing the door frames 4A in

place, include brackets 13 detachably secured in any suitable manner to the buckstays 14 as by screws connecting the brackets to the webs of the buckstays 14. The brackets 13 project in front of the adjacent door frame flanges 410 and 5 are threaded for the passage of clamping screws 15 which bear at their inner ends against the door frame flanges. Asbestos or other packing material 17 may be interposed between each door frame flange 410 and the corresponding flash 13 plate 16. With the construction shown in Figs. 3 and 4, each door frame may be freed from the buckstays for removal, by the disconnection of the corresponding brackets 13, and the removal of a door frame facilitates door frame and heating wall repairs exactly as with the construction shown in Figs. 1 and 2.

The embodiment of the invention shown in Figs. 5 and 6 differs from that shown in Figs. 3 and 4 in respect to the means employed for anchoring the door frames in place. In Figs. 5 and 6, the door frame flanges 410 of the door frame members 4B are formed with bolt holes for the passage of bolts 18 by which the flanges 410 of each door frame are bolted to the adjacent flash plates 16. As shown the bolts 18 are stud bolts anchored in the flash plates, and the latter may be provided with reinforcing pads or nut portions 18' at their rear sides to improve the anchorage for the stud bolts 18. With the arrangement shown in Figs. 5 and 6, all that is required to free a door frame member for removal is the removal of the nuts 18' on the outer ends of the corresponding stud bolts.

This application is a continuation in part of my prior application, Serial No. 707,455 filed January 20, 1934.

While in accordance with the provisions of the statutes, I have illustrated and described the best form of embodiment of my invention now known to me, it will be apparent to those skilled in the art that changes may be made in the form of the apparatus disclosed without departing from the spirit of my invention as set forth in the appended claims and that in some cases certain features of my invention may be used to advantage without a corresponding use of other features.

Having now described my invention, what I claim as new and desire to secure by Letters Patent, is:

1. In a coke oven structure of the type comprising horizontally elongated coking chambers and masonry heating walls arranged alternately in a row and removable doors for closing the ends of said chambers, the combination with a buckstay in front of and supporting each of the heating wall ends adjacent and at the opposite sides of a coking chamber end, of a rigid metallic door frame member forming a frame for the door at said chamber end and connecting members adapted to connect each side of said frame member to the adjacent buckstay and interposed between the latter and the adjacent heating wall end and adjustable transversely of the buckstay into and out of positions in which they overlap the adjacent side of said frame member.

2. In a coke oven structure of the type comprising horizontally elongated coking chambers and masonry heating walls arranged alternately in a row and removable doors for closing the ends of said chambers, the combination with a buckstay in front of and supporting each of the heating wall ends adjacent and at the opposite

- sides of a coking chamber end, of a rigid metallic door frame member forming a frame for the door at said chamber end and connecting members adapted to connect each side of said frame member to the adjacent buckstay and interposed between the latter and the adjacent heating wall end and adjustable transversely of the buckstay into and out of positions in which they overlap said frame member, each of said heating wall ends being recessed to receive said connecting members. 5
3. In a coke oven structure of the type comprising horizontally elongated coking chambers and masonry heating walls arranged alternately in a row and removable doors for closing the ends of said chambers, the combination with a buckstay in front of and supporting each of the heating wall ends adjacent and at the opposite sides of a coking chamber end, of a rigid metallic door frame member forming a frame for the door at said coke oven chamber end, connecting members adapted to connect each side of said frame member to the adjacent buckstay and interposed between the latter and the adjacent heating wall end and adjustable transversely of the buckstay into and out of positions in which they overlap said frame member and screws mounted in said connecting members and adapted when the latter overlap said frame member to engage the latter. 10
4. In a coke oven structure of the type comprising horizontally elongated coking chambers and masonry heating walls arranged alternately in a row and removable doors for closing the ends of said chambers, the combination with a buckstay in front of and supporting each of the heating wall ends adjacent and at the opposite sides of a coking chamber end, of a rigid metallic door frame member forming a frame for the door at said chamber end, connecting members adapted to connect each side of said frame member to the adjacent buckstay and interposed between the latter and the adjacent heating wall end and adjustable transversely of the buckstay into and out of positions in which portions of said connecting members overlap said frame member and adjustable clamping means acting between said door frame member and the portions of said connecting members which overlap said frame member. 15
5. In a coke oven of the type comprising horizontally elongated coking chambers and masonry heating walls arranged alternately in a row and removable doors for closing the ends of said chambers, the combination with a buckstay in front of and supporting each of the heating wall ends adjacent and at the opposite sides of a coking chamber end, of a rigid metallic door frame member forming a frame for the door at said chamber end, connecting members adapted to connect each side of said frame member to the adjacent buckstay and interposed between the latter and the adjacent heating wall end and adjustable transversely of the buckstay into and out of positions in which portions of said connecting members overlap the adjacent side of said frame member and wedges interposed between said frame member and the portions of said connecting members overlapping said frame member. 20
6. In a coke oven of the type comprising horizontally elongated coking chambers and masonry heating walls arranged alternately in a row and removable doors for closing the ends of said chambers, the combination with a buckstay in front of and supporting each of the heating wall ends adjacent and at the opposite sides of a coking chamber end, of a flash plate between each heating wall end and the buckstay in front of said wall end a rigid metallic door frame member forming a frame for the door at said chamber end and having a body portion extending between said flash plates into, and forming a lining for, said chamber end and having side portions in front of and overlapping adjacent portions of said flash plates connecting means detachably connected to said buckstay and overlapping the sides of said frame member, said connecting means including frame member engaging parts adjustable to adjustably clamp said frame member in place. 25
7. In a coke oven of the type comprising horizontally elongated chambers and masonry heating walls arranged alternately in a row and removable doors for closing the ends of said chambers, the combination with a buckstay in front of each of the heating wall ends adjacent and at the opposite sides of a coking chamber end, of a flash plate interposed between each of said wall ends and the buckstay in front thereof with a portion extending horizontally away from the buckstay toward but terminating short of the adjacent side of said chamber end, a rigid metallic door frame member forming a frame for the door at said chamber end and including side flange portions each overlapping the said flash plate portion adjacent thereto, and means adapted to act between each buckstay and the adjacent side of said frame member and hold the latter in engagement with the corresponding flash plate portion but adjustable to permit the removal of said frame member without removal of said buckstays and flash plate members. 30
8. In a coke oven of the type comprising horizontally elongated chambers and masonry heating walls arranged alternately in a row and removable doors for closing the ends of said chambers, the combination with a buckstay in front of each of the heating wall ends adjacent and at the opposite sides of a coking chamber end, of a flash plate interposed between each of said wall ends and the buckstay in front thereof with a portion extending horizontally away from the buckstay toward but terminating short of the adjacent side of said chamber end, a rigid metallic door frame member forming a frame for the door at said chamber end and including side flange portions each overlapping the said flash plate portion adjacent thereto, and clamping members mounted on said buckstays and including portions normally in overlapping engagement with said frame member and clamping the side flange portions thereof against said flash plate portions but movable out of said engagement to permit the removal of said frame member. 35
9. In a coke oven of the type comprising horizontally elongated chambers and masonry heating walls arranged alternately in a row and removable doors for closing the ends of said chambers, the combination with a buckstay in front of each of the heating wall ends adjacent and at the opposite sides of a coking chamber end, of a flash plate interposed between each of said wall ends and the buckstay in front thereof with a portion extending horizontally away from the buckstay toward but terminating short of the adjacent side of said chamber end, a rigid metallic door frame member forming a frame for the door at said chamber end and separable connections between each of said flash plate portions and adjacent portions of said frame member for releasably securing the latter to said flash plates. 40
10. In a coke oven of the type comprising horizontally elongated chambers and masonry heating walls arranged alternately in a row and removable doors for closing the ends of said chambers, the combination with a buckstay in front of each of the heating wall ends adjacent and at the opposite sides of a coking chamber end, of a flash plate interposed between each of said wall ends and the buckstay in front thereof with a portion extending horizontally away from the buckstay toward but terminating short of the adjacent side of said chamber end, a rigid metallic door frame member forming a frame for the door at said chamber end and separable connections between each of said flash plate portions and adjacent portions of said frame member for releasably securing the latter to said flash plates. 45

zontally elongated chambers and masonry heating walls arranged alternately in a row and removable doors for closing the ends of said chambers, the combination with a buckstay in front of each of the heating wall ends adjacent and at the opposite sides of a coking chamber end, of a flash plate interposed between each of said wall ends and the buckstay in front thereof with a portion extending horizontally away from the 5 buckstay toward but terminating short of the adjacent side of said chamber ends, a rigid metallic door frame member forming a frame for the door at said chamber end and including side flange portions each overlapping the said flash 10 plate portion adjacent thereto, and bolted connections between the overlapping flange and flash plate portions.

11. The combination with a coke oven structure of the type comprising a horizontally elongated coking chamber and masonry heating walls 15 at the sides of the chamber having recesses at their corners forming a door frame receiving enlargement of the end of the chamber, of a buckstay in front of and supporting each of the heating wall ends adjacent one end of said chamber, a flash plate between each heating wall end and the corresponding buckstay, with a portion extending horizontally away from the buckstay toward, but not overlapping the adjacent recess, 20 a metallic door frame member extending between the two flash plates with an inner portion, received in the said recesses, and with an outer

portion projecting outwardly beyond said flash plates, and comprising flange portions at its opposite sides overlapping said flash plates, and door frame securing means acting between the door frame member and the adjacent buckstays 5 in the direction to hold said flange portions against said flash plates and adjustable to permit the removal of the door frame member without removal of the flash plates and buckstays.

12. In a coke oven of the type comprising horizontally elongated coking chambers and masonry heating walls arranged alternately in a row and removable doors for closing the ends of said chambers, the combination with a buckstay in front of and supporting each of the heating 15 wall ends adjacent and at the opposite sides of a coking chamber end, of a flash plate between each heating wall end and the buckstay in front of said wall end a rigid metallic door frame member forming a frame for the door at said chamber end and having a body portion extending between said flash plates into, and forming a lining for, 20 said chamber end and having side portions in proximity to adjacent portions of said flash plates, joint packing material sealing the joint between said side and adjacent portions, connecting means detachably connected to said buckstays and overlapping the sides of said frame member, said connecting means including frame member engaging parts adjustable to adjustably 25 clamp said frame member in place.

WILHELM BEIMANN.
